9 Claims. (Cl. 184—7)

1

This invention relates to lubricating apparatus, and more particularly to centralized lubricating systems in which a plurality of measuring valves are periodically supplied and actuated from a single source.

One object of the invention is to provide a new and improved timing mechanism for automatically initiating the operation of such a lubricating system at predetermined intervals.

Another object of the invention is to provide a timing mechanism for controlling the duration of each period of operation of the system.

A further object of the invention is to provide a timing mechanism which is readily adjustable to vary the frequency of operation of a centralized lubricating system.

It is also an object of the invention to provide a timing mechanism which is readily adjustable to vary the duration of each period of intermittent operation of a centralized lubricating system.

An additional object of the invention is to provide a centralized lubricating system with a control mechanism which automatically initiates the operation of the system at predetermined intervals for supplying lubricant under pressure throughout the system, and to provide as a part of the control mechanism, a warning signal which is automatically actuated in the event of the failure of pressure or exhaustion of the lubricant.

Other objects and advantages of the invention will appear from the following description taken in connection with the drawings, in which:

Fig. 1 is a front elevation of the control apparatus for a lubricating system including the timing mechanism which is the subject of this invention;

Fig. 2 is a rear elevation of the control mechanism;

Fig. 3 is a face view of the frequency cam disc of the timing mechanism and its masking disc in assembled relation;

Fig. 4 is a face view of the masking disc alone;

Fig. 5 is a face view of the duration cam disc and its masking disc in assembled relation;

Fig. 6 is a face view of the masking disc for the duration cam;

Fig. 7 is a sectional view taken diametrically through the frequency cam, the duration cam and their masking discs as assembled on their co-axial drive shafts in the timing mechanism;

Fig. 8 is a diagrammatic view of the lubrication system of the dual type with a wiring diagram of the timing mechanism as associated therewith for controlling the system;

Fig. 9 is a diagrammatic view of a centralized lubricating system of the single line type, together with a wiring diagram of the timing mechanism as associated therewith for controlling the system.

There are various types of centralized lubri-

2

cating systems by which lubricant is distributed to a plurality of bearings or other surfaces requiring lubrication, in which distribution occurs intermittently but preferably at regular intervals.

5 In such systems, each bearing or other point requiring lubrication is fitted with a measuring valve and these valves are connected together by conduits by which they are each filled with a predetermined quantity of lubricant. Then by application of pressure to the lubricant in the connecting conduits, the valves are actuated to discharge their lubricant to the individual bearings. In a single line system, the measuring valves are connected in a series and the pressure is applied in one direction only, from the pump or other source of pressure through the system to the last valve of the series. In a dual line system, the measuring valves are connected in a closed series or loop which extends from the pump or compressor and returns to it so that pressure may be applied through the series in either direction. In these dual systems, each measuring valve is filled by the application of pressure to the system in one direction and is then discharged by the application of pressure in the opposite direction. A complete operation of the system usually consists in the application of pressure first in one direction, causing each of the valves to deliver a charge of lubricant previously acquired and at the same time refilling another chamber of the valve with lubricant; the operation is then completed by reversing the pressure through the system causing each of the valves to deliver the charge of lubricant just acquired and to be refilled for a subsequent operation. Since each valve delivers two charges of lubricant at each operation of the system, such a valve may have connections to two different bearings to be lubricated successively during the complete cycle of operation. In the single line system, a single application of pressure delivers a charge of lubricant from each of the valves and then refills the valves in preparation of the next periodic operation of the system.

Either system may be operated manually and at will at intervals depending upon the judgment of the operator, but in many cases it is preferable that the intermittent operation be automatically controlled and timed, and this is the function of the mechanism embodying this invention. The timing mechanism disclosed herein is claimed in divisional application Serial No. 12,807, filed March 3, 1948 and entitled "Timing Mechanism."

In Figs. 1 and 2, the timing mechanism is shown associated with valve devices intended for operation of a dual line system, and Fig. 8 shows such a system diagrammatically. The control devices are supported on a panel board 10 and the timing mechanism is actuated by an electric clock 12, preferably driven by a synchronous

motor and having the usual shafts 14 and 16 telescopically arranged as indicated in Fig. 7. Preferably the shaft 14 corresponds to that which drives the hour hand of the clock and for the purpose of this invention, makes one revolution in twenty-four hours. The shaft 16 corresponds to that which drives the minute hand of the clock and makes one revolution each hour. Instead of an hour hand, the shaft 14 carries the frequency cam disc 18, and instead of a minute hand, the shaft 16 carries the duration cam disc 20. Each of said discs has peripheral notches or recesses for actuating electric switches, and the frequency cam 18 has associated with it a masking disc 19, while the duration cam 20 has associated with it a masking disc 21, said masking discs determining which of the recesses or notches of the cams shall be operative at any given time.

The frequency cam 18, as shown, has twelve notches or recesses 22 spaced at equal intervals so that a stationary follower element cooperating therewith may be actuated every two hours as the cam 18 rotates. If the lubricating system is to be operated at two hour intervals, the masking disc 19, which is mounted co-axially with the disc 18, will be rotatively adjusted to uncover all the recesses 22, but if operation at less frequent intervals is desired, the disc 19 may be shifted so that certain portions of its periphery will cover certain of the notches 22, leaving less than twelve of them effective for actuating such a follower. As shown in Fig. 3, the disc 19 is adjusted to uncover only three of the notches 22, thus providing for operation of a lubricating system at eight hour intervals. The masking disc 19 is formed as shown in Fig. 4 with peripheral recesses so arranged that it can be adjusted with respect to the disc 18 so as to provide for operation of the system either at two hour intervals, at four hour intervals, at eight hour intervals, at twelve hour intervals or only once in each twenty-four hours.

As shown in Fig. 7, the frequency cam disc 18 is secured rigidly to a hub 23 which is fixed to the hollow shaft 14 by a set screw 24. The masking disc 19 is rotatably mounted on the hub 23 but is held in face to face contact with the cam disc 18 by means of a coil spring 26 on the hub. A small boss or detent projection 29 on the face of the disc 19 is adapted to fit in any one of the five openings 28 in the disc 18, and as shown in Fig. 3, said openings are marked respectively with the numerals 24, 12, 2, 8 and 4 to designate the intervals at which the system will be operated when the masking disc is adjusted with its detent projection 29 in any one of said openings 28. To facilitate such adjustment, the masking disc is provided with diametrically projecting lugs 30 by which it may be grasped between the thumb and finger and forced away from the disc 18 (against the pressure of the spring 26) to release the projection 29 from one of the openings 28, and then rotated to register the projection with another opening 28.

The duration cam disc 20, as shown in Fig. 5, has a series of peripheral notches or recesses 32 which differ in circumferential extent and correspond respectively to periods of one to five minutes for active operation of a lubrication system. In other words a follower device which controls operation of the system drops into one of the notches 32 and the system continues to operate until the follower is cammed out of the notch. To determine which of the notches 32 shall be effective, the masking disc 21, which is associated with the cam disc 20, has a plain peripheral por-

tion 34 and a single notch 31, which is of the same width as the widest of the notches 32. By rotative adjustment of the disc 21, this notch 31 may be registered with any of the several notches 32 so as to expose a selected one of them while the plain circular portion 34 of the disc 21 covers the remaining notches 32. For a special purpose, to be later explained, the masking disc 21 has an additional notch 35 with its leading edge 35a disposed diametrically opposite the middle of the notch 31; and a corresponding portion 37 of the periphery of the cam disc 20 is of reduced diameter so as to expose or uncover the notch 35 at any of the several positions of adjustment of the masking disc with respect to the cam disc. At each of these positions of adjustment, the notch 31 is centered with respect to the notch 32 which it exposes; consequently the leading edge of the notch 35 is always disposed diametrically opposite the uncovered notch 32 so that the follower of a control device positioned to engage in the notch 35 will do so at the middle of the timing period represented by the active or exposed notch 32.

The cam disc 20 has an opening 38 opposite each of the notches 32 and the masking disc 21 has a small boss or projection 39 adapted to enter any one of the openings 38 when the disc 21 is suitably adjusted about its axis. As seen in Fig. 7, the disc 21 is fixed to a hub 33 which is secured to the shaft 16 by a set screw 34 and the coil spring 36 on said hub presses the cam disc 20 into face to face contact with the disc 21. The cam disc is rotatable on the hub and is provided with lugs or finger pieces 40, by which it may be pulled forward out of contact with the disc 21, so as to release the detent boss 39 from one of the openings 38 and permit rotation of the disc 21 to register the boss with any other opening 38. In Fig. 5 the openings 38 are marked respectively 1—M, 2—M, 3—M, 4—M and 5—M to indicate that the notches will effect operation of the system for periods of from one to five minutes respectively, and as shown, the detent 39 is registered in the opening 38 corresponding to the three minute period.

Since the cam discs 18 and 20 are similar in size and the disc 20 and its masking disc 21 are located in front of the surface of the frequency cam 18, the discs 20 and 21 are provided with segmental windows 41 and 42 which may be registered with each other, and then rotated into registration with the openings 28 of the disc 18 as shown in Fig. 1. This permits adjustment of the masking disc 19 to the desired position after which the discs 20 and 21 may be adjusted relative to each other as desired.

In addition to the clock 12 and the timing cams just described, the panel 10 supports three switches 50, 60 and 70 which may be of the "microswitch" type having actuating arms 51, 61, 60 and 71 respectively, extending for engagement with the cam discs. These switches control the supply of current to solenoids which are mounted on the rear face of the panel 10 as seen in Fig. 2, and which are designated respectively by the numerals 81, 82, 83 and 84. The plungers of solenoids 81 and 82 are aligned and connected together for simultaneous movement, and similarly the plungers of solenoids 83 and 84 are aligned and connected together. Solenoids 81 and 82 are thus arranged to actuate a lever 85 which is fulcrumed to extend through the panel board 10 and is connected to the stem 86 of a valve 87 for actuating it. Similarly the solenoids 83 and 84 are connected to a lever 88 which is fulcrumed in the panel board 10 and which actuates the stem 89

of a valve 90. The valves 87 and 90 may be spool valves or slide valves of any suitable internal design and are diagrammatically illustrated in Fig. 8. A lubricant supply pipe 91 extends to a T-fitting 92 having branches 93 and 94 connected to the valves 87 and 90 respectively. The valve 87 has a feed pipe 95 for connection with one end of the lubrication system, and the valve 90 has a feed pipe 96 for connection with the other end of the system. A vent pipe 97 is shown extending from the valve 87 and the vent pipe 98 extends from the valve 90.

In Fig. 8 the diagram shows the supply pipe 91 leading from the air operated lubricant compressor at 100, while the vent or return pipes 97 and 98 lead from the valves 87 and 90 to said compressor. The feed pipe 95 is shown leading from the valve 87 to a series of measuring valves 102 which operate as already described and each of which is provided with two outlet tubes 104 and 105 which may lead to separate bearings, or which in some cases may both lead to the same bearing if it is of a character requiring an unusual amount of lubrication. Conduits 106 of tubing connect the valves 102 and the final valve of the series is connected by the pipe 96 to the control valve 90 on the panel board 10. The air motor for operating the compressor at 100 is not shown in detail in the drawings, but compressed air for actuating it may be understood as being supplied through the pipe 107 which leads from a valve 108 having an air pressure supply pipe 109 and a vent pipe 110; the valve is shown with a solenoid 112 for actuating it. The solenoid 112 and the air valve 108 are seen in Fig. 2 mounted on the rear face of the panel board 10.

From the previous explanation, it will be understood that the function of the timing mechanism and the valves 87 and 90 is to initiate the operation of the compressor 100 at predetermined intervals and then to maintain such operation for a predetermined period of from one to five minutes during which period the lubricant is first fed out through the pipe 95 and through the series of measuring valves 102, until all said valves have been discharged and refilled, whereupon a portion of the lubricant will flow through the pipe 96 and valve 90 back to the compressor by way of the return pipe 98. Then the valves 87 and 90 will be reversed to cause an outflow of lubricant through the pipe 96 and measuring valves 102 and back by way of the pipe 95, valve 87 and return pipe 97. The manner in which this is accomplished by the timing mechanism may be best understood by reference to the wiring diagram in Fig. 8. The current supply is furnished by lead wires 120 and 121 controlled by a main switch at 122, and when the switch 122 is closed, the clock 12 is energized through conductors 124 and 125. Whenever an exposed notch 22 of the frequency cam 18 registers with the follower 51 of the switch 50, the switch is closed at the contact 52 from which a conductor 53 leads to the contact point 62 of the switch 60. While the follower 51 is still engaged in the notch of the frequency cam 18, the follower 61 of the switch 60 engages in the exposed notch 32 of the duration cam 20 and thus causes the switch 60 to close at contact 62. Since the switch 50 is connected by conductor 54 with the main lead wire 121, this completes a circuit from switch 60 through conductor 63, solenoid 112 and conductor 64, which is connected with the other lead wire 120.

The switch 60 is also connected by a conductor

65 to the switch 70 and at the beginning of the period controlled by the cam 20, the follower 71 of switch 70 will be riding on the circular periphery 34 of the masking disc 21. With the follower in this position, the arm of the switch 70 engages the contact 72 which is connected by conductor 73 to the solenoids 81 and 84. The circuit through said solenoids is completed by conductors 74 and 75, the latter being connected to the lead wire 120. With the solenoids thus energized, the valve members of the valves 87 and 90 will be positioned as shown in Fig. 8 and since the solenoid 112 has been simultaneously energized, the air operated lubricant compressor at 100 will be furnishing lubricant under pressure through the pipe 91 and branch 93 to the chamber of the valve 87, and then by way of pipe 95 to the measuring valves 102 of the system. The time required for the lubricant to actuate all the valves 102 in the system and complete its circuit back to the valve 90 and vent or return pipe 98 will have been determined, and the operative notch or recess 32 of the duration cam will have been selected in view of this determination. By the time the lubricant has completed its circuit, the cam 20 will have advanced through about one-half of the length of the notch 32 and the follower 71 will then drop into the notch 35 in which it will ride for the remainder of the period. With the follower 71 in this position, the arm of the switch 70 will be shifted from contact 72 to contact 76 which is connected by the conductor 77 with solenoid 83 and by conductor 78 with solenoid 82. The separation of the switch arm from contact 72 will deenergize the solenoids 81 and 84, and its engagement with contact 76 will then energize solenoids 83 and 82, causing reversal of the valves 87 and 90. Thereupon the lubricant, being supplied under pressure through the pipe 91 and branch 94, will flow from the valve 90 through the pipe 96 and thence through the several measuring valves 102 of the system, returning by way of pipe 95, valve 87 and vent pipe 97 to the compressor at 100.

As the cam disc 20 continues to turn, the follower 61 will ride out of the notch 32, disengaging the arm of the switch 60 from the contact 62 and breaking the circuit of the solenoid 112, thus permitting the air valve 108 to shift into a position at which the air pressure is cut off from the air motor which operates the lubricant compressor 100. Thereupon the pressure in the system is vented through the pipe 97 and no further delivery of lubricant is effected for the time being. The continued rotation of the cam disc 18 causes the follower 51 to ride out of the notch 22 and to open the switch 50 which then remains open until the next effective notch 22 of the disc 18 registers with the follower 51.

Fig. 8 shows a branch pipe 130 leading from the supply pipe 91 to a pressure responsive device 131 which consists of a cylinder containing a spring pressed piston having a stem 132 which protrudes slidably from the end of the cylinder. If a satisfactory pressure is developed in the pipe 91 by the operation of the compressor at the beginning of a lubrication period, the stem 132 will be protruded sufficiently to disengage the arm of switch 140 from the contact 141. However, if this should not occur, either because the supply of lubricant available to the compressor 100 has been exhausted or because the compressor is not functioning properly, the engagement of the follower 71 in the notch 35 will establish a circuit through a relay switch 142 for lighting a red warning sign.

nal lamp 143 and actuating an audible signal 144, such as an electric horn. The circuit which is thus established is controlled by the magnet coil 145 of the relay switch 142. Said coil is energized through the switch 140 by a circuit which includes the lead wire 121, conductor 54, switch 50, conductor 53, switch 60, conductor 65, switch 70, conductors 77 and 78, switch 140, conductor 146, magnet coil 145, conductor 147, conductor 125 and lead wire 120. The switch 142 is connected with the lead wire 121 and conductor 54 by conductor 148 and the switch arm is held normally in engagement with contact 149 from which conductor 150 leads to a green signal lamp 151. The circuit for this lamp is completed through conductors 147 and 125 to the lead wire 120 so that the green lamp 151 normally burns whenever the main switch 122 is closed. But if the relay coil 145 is energized, it withdraws the latch 152 from the switch 142 and permits the switch arm to spring into engagement with contact 153 from which the conductor 154 leads to the red warning lamp 143 and the signal horn 144.

Thus if the operation of the system proceeds normally, causing pressure to be built up in the pipe 130, the switch 140 will be opened before the second half of the cycle in which the follower 71 engages the notch 35 of the duration cam 20, and the green signal light 151 will burn continuously; but if satisfactory pressure fails to be attained in the first half of the period controlled by the duration cam 20, the pressure responsive stem 132 will not be lifted and the switch 140 will remain closed, thus permitting the relay switch 142 to be unlatched and to energize the warning signals 143 and 144. The switch 142 will then remain unlatched so that the red light will continue to burn and the horn will continue to sound until the switch 142 is manually reset, thus requiring the operator of the machine or apparatus to give it attention and determine the cause of failure of the lubrication system.

As another example of the use of the timing mechanism embodying this invention, Fig. 9 illustrates diagrammatically a portion of a single line centralized lubricating system and includes a wiring diagram of the control devices actuated by the timing mechanism. In this case the system is shown as having a lubricant compressor 200 driven by an electric motor 201 and having a supply pipe 202 leading from any suitable source of lubricant supply, with a feed pipe 203 leading to a series of measuring valves 204. Connecting conduits 205 extend between successive valves of the series, but there is no return connection as in the case of the system shown in Fig. 8. Admission of lubricant under pressure to the valves 204 is controlled by any suitable form of valve, which is indicated diagrammatically at 206 on Fig. 9. This valve is connected to the line 203 by a branch pipe 207 so that when the valve is open, the line 203 is vented through the vent pipe 208 which leads from the valve 206. If the valve is closed, the vent 208 is closed and pressure developed in the line 203 is transmitted to the measuring valves 204.

The timing mechanism consists of the clock 12, the frequency cam 18 and the duration cam 20 as in the structure already described. The supply of electrical energy is obtained through the main lead wires 120 and 121 under control of the main switch 122, and when the switch 122 is closed, the clock 12 is connected into a circuit comprising conductor 209, conductor 210 and conductor 211. The clock then continues to run

and when the follower 51 engages a notch in the frequency cam 18, the arm of the switch 50 engages contact 52 from which the conductor 53 leads to the arm of switch 60. The switch 50 is connected to lead wire 121 by conductor 212. In this arrangement the switch 60 is a double throw switch and its arm normally engages a contact 213 from which the conductor 214 leads to the solenoid coil 215; from this coil the circuit is completed through conductor 216 and lead wire 120.

As soon as the follower 61 engages a notch in the duration cam 20, the arm of switch 60 is separated from contact 213, thus opening the circuit 15 of solenoid 215. The switch arm then engages contact 217 from which conductor 218 leads to the coil 219 of a relay switch 220, which controls the driving motor 201 for the pump 200. From the coil 219, conductors 221 and 222 complete the relay circuit by connection with the lead wire 120. The switch 220 is connected by conductor 223 with the conductor 211 leading from the feed wire 121, and the contact point 224, which the arm of the switch 220 engages is connected to the motor 201 by conductor 225; the motor circuit is completed by conductors 226 and 222 leading to the feed wire 120.

In addition to starting the motor 201, the closing of the relay switch 220 energizes the solenoid 227 which is connected to the contact point 224 of the switch by conductors 228 and 229, the circuit for the solenoid being completed through conductor 216 and lead wire 120. Thus simultaneously with the starting of the pump 200, the valve 206 is closed by the solenoid 227 so that pressure generated by the pump will be transmitted through the line 203 to the measuring valves 204. The pump 200 continues to operate until the follower 61 rides out of the notch in the duration cam 20, whereupon the arm of switch 60 is disengaged from the contact 217, thus opening the motor circuit and also opening the circuit of solenoid 227, while engagement of the arm with contact 213 closes the circuit of solenoid 215 and shifts the valve to its venting position.

A branch pipe 230 is connected into the pressure line 203 and is fitted with a pressure responsive device comprising a cylinder 231 with a stem 232 adapted to be protruded by the application of pressure through the pipe 230. During the first half of the operating period determined by the cam 20, the pressure in the line 203 should build up sufficiently to protrude the stem 232 and open the switch 140 which is connected by a conductor 233 with the contact point 234. After the first half of the operating period, the follower 71 will occupy the notch 35 in the masking disc of the duration cam 20, thus bringing the switch arm 70 into engagement with the contact point 234. The switch 70 is connected by a conductor 235, conductor 228, relay switch 220 and conductor 211 to the lead wire 121, and if the pressure built up in the line 203 and branch line 230 is insufficient to open the switch 140, a circuit will be completed from the switch 70 through conductor 232, switch arm 140, contact 141, conductor 146, relay coil 145, conductor 147 and conductor 222 to the lead wire 120. The latching relay 142, identical with that already described, normally maintains its switch arm in engagement with the contact 149 which is connected by conductor 150 with a green signal lamp 151. The relay switch 142 is connected by conductor 148 to conductor 211 and then to the lead wire

121. The lamp 151 is connected by conductors 147 and 222 to the lead wire 120; hence the circuit for the green lamp 151 is normally closed through the relay 142 whenever the main switch 122 is closed. But the energizing of the coil 145 withdraws the latch 152 from the relay switch arm and permits the latter to engage the contact 153 which is connected by conductor 154 to the red warning signal lamp 143 and to the audible signal 144 for which the energizing circuit is completed through conductors 147, 222, and lead wire 120.

Thus if satisfactory pressure is built up in the line during the first half of the operating cycle, the stem 232 will be protruded and will open the switch 140 so that as the follower 71 is engaged in the notch 35, the relay 145 will not be energized and the green light 151 will continue to burn. However, if the supply of lubricant is exhausted or for some other reason the proper pressure is not developed in the line 203 during the first half of the cycle, the stem 232 will not be protruded so as to open the switch 140, and as a consequence the relay coil 145 will be energized by closing of the switch 70 and the red warning light will be lighted and the audible signal will be sounded. The latching relay must be reset manually to shut off the warning signals and to restore the circuit for the green light, thus insuring that the operator will take occasion to learn the reason for failure of the apparatus to develop the proper pressure.

It will be understood that the applications of the timing mechanism to a dual line system, as shown in Fig. 8, and to a single line system, as shown in Fig. 9, are only illustrative and that this timing mechanism may be readily adapted to the control of various other systems, both in the lubrication field and elsewhere. It will also be recognized that while there is shown and described herein certain structure embodying the invention and illustrative thereof, the invention is not limited to the specific forms shown but embraces all changes and modifications in its various features and all equivalents thereof coming within the scope of the appended claims.

I claim:

1. In a lubrication system which includes a series of measuring valves each adapted to deliver lubricant in response to pressure applied to the valve, conduit means connecting said valves, a supply of lubricant, conduit means connecting said valves to said supply, and a pump operable to feed lubricant under pressure from said supply to said valves, a timing mechanism comprising a clock, a frequency cam and a duration cam driven by the clock, switches actuated by said cams respectively, electrically controlled driving means for said pump, control valve means between the outlet of the pump and the inlet to the system governing the application of pressure from the pump to the measuring valves and bypassing of lubricant from the valves, solenoid means operatively connected to actuate said control valve means, a source of electrical energy and a circuit which includes said electrically controlled pump driving means, said solenoid means and said switches, said switches being actuated by said cams at predetermined intervals and for predetermined periods to energize said pumping means and to operate said valve means for supplying lubricant to the measuring valves.

2. In a lubrication system which includes a series of measuring valves each having two ports from which lubricant is delivered alternately in response to flow through the valve, first in one

direction and then in the opposite direction, conduit means connecting said valves in a closed circuit, a supply of lubricant included in said circuit, and a pump operable to feed lubricant through said circuit in either direction, a timing mechanism comprising a clock, a frequency cam and a duration cam driven by the clock, a frequency switch and a duration switch actuated by said cams, respectively, and connected together in series, a source of electrical energy and electrically controlled driving means for said pump connected in a circuit with said switches and said energy source, said switches being closed at predetermined intervals and for predetermined periods to energize said pumping means, together with reversible valve means to control the direction of flow of lubricant through said series of measuring valves, solenoid means operatively connected to actuate said valve means, and a third switch controlling said solenoid means, said duration cam being formed to actuate said third switch substantially at the middle of each period of operation of the pump for operating said valve means to reverse the flow of lubricant through the measuring valves.

3. In a lubrication system which includes a series of measuring valves, conduit means connecting said valves in a closed circuit, each valve being adapted to deliver lubricant in response to pressure applied to the valve, first in one direction and then in the opposite direction, a supply of lubricant included in said circuit, and a pump operable to feed lubricant through said circuit under pressure in either direction, a timing mechanism comprising a clock, a frequency cam and a duration cam driven by the clock, a frequency switch and a duration switch actuated by said cams, respectively, and connected together in series, a source of electrical energy and electrically controlled driving means for said pump connected in a circuit with said switches and said energy source, said frequency cam operating one of said switches at predetermined intervals to determine the frequency at which said circuit is conditioned for operating said pump and said duration cam operating the other of said switches to control the duration of a lubricating cycle together with reversible valve means to control the direction of flow of lubricant through said series of measuring valves, solenoid means operatively connected to actuate said valve means, and a third switch controlling said solenoid means, said duration cam being formed to actuate said third switch substantially at the middle of each period of operation of the pump for operating said valve means to reverse the direction in which pressure is applied to the measuring valves.

4. In a lubrication system which includes a plurality of measuring valves each adapted to deliver lubricant in response to the application of pressure, conduit means connecting said valves in sequence, a supply of lubricant, and a pump connected to feed lubricant from said supply to said measuring valves, bypass forming means for said system, a timing mechanism comprising a clock, a frequency cam and a duration cam driven by said clock, a frequency switch and a duration switch actuated by said cams, respectively, and connected in series, electrically controlled driving means for said pump, a control valve between the outlet of the pump and the inlet to the system adjustable to a first position for applying the pump pressure to the measuring valves and to a second position for connecting said pump and the system to said bypass means, solenoid

means for shifting said valve, a source of electrical energy and a circuit which includes said electrically controlled pump driving means, said solenoid means and said switches, said duration cam serving to start the pump and energize the solenoid means for shifting the valve to said first position at the beginning of a period of operation and to shut off the pump and energize the solenoid means for shifting the valve to its said second position at the end of said period.

5. In a lubrication system as defined in claim 2 an electrically energized warning signal, a circuit by which it is connected with said source of electrical energy, a normally closed switch in said circuit, and a normally open switch in said circuit, a pressure responsive device connected to a lubricant conduit leading from the pump to said measuring valves and operable in response to a predetermined pressure to open said normally closed switch, said normally open switch being the said third switch which is closed substantially at the middle of the period of operation of the pump and thus energizes the signal unless the pump has developed the predetermined pressure sufficient to open the normally closed switch.

6. In a lubrication system which includes a series of measuring valves each adapted to deliver lubricant in response to pressure applied to the valve, conduit means connecting said valves, a supply of lubricant, conduit means connecting said valves to said supply and an electrically controlled pump operable to feed lubricant under pressure from said supply to said valves, solenoid operated control valve means governing the application of pressure from the pump to the measuring valves and bypassing of lubricant from the valves, a timing mechanism, a frequency switch and a duration switch operated by said timing mechanism to energize said valve means and pump, a source of electrical energy and a circuit which includes said pump, valve means and timing mechanism, and a third switch in said circuit initially energizing said solenoid operated control valve means to operate the same in one direction, said switch being operated by said timing mechanism at an intermediate point in each cycle of operation of the pump to energize said solenoid operated valve means for moving the control valve to another position.

7. In a lubrication system which includes a series of measuring valves each adapted to deliver lubricant in response to pressure applied to the valve, conduit means connecting said valves, a supply of lubricant, conduit means connecting said valves to said supply and a pump operable to feed lubricant under pressure from said supply to said valves, control valve means governing the application of pressure from the pump to the measuring valves, timing mechanism for actuating said pump and said control valve means at predetermined intervals and for predetermined periods for supplying lubricant to the measuring valves, electrically energized warning signals including a signal for indicating the presence of a predetermined pressure in the system, and a signal operable at a pressure below said predetermined pressure, a circuit for said signals including a normally closed switch controlling energization of said first signal, and a normally open switch controlling energization of said second signal, electrically energized means for simultaneously reversing the position of said switches, a circuit for energizing said means including a switch actuated to closed position by said timing mechanism at a predetermined interval after said

pump is energized, and pressure responsive means for opening said circuit in advance of the closing of said last mentioned switch when a predetermined pressure is developed in the system.

8. In a lubrication system which includes a series of measuring valves each adapted to deliver lubricant in response to pressure applied to the valve, conduit means connecting said valves, a supply of lubricant, conduit means connecting said valves to said supply, and a pump operable to feed lubricant under pressure from said supply to said valves, a timing mechanism comprising a clock, a frequency cam and a duration cam driven by the clock, switches actuated by said cams respectively, electrically controlled driving means for said pump, control valve means governing the application of pressure from the pump to the measuring valves and bypassing of lubricant from the valves, solenoid means operatively connected to actuate said control valve means, a source of electrical energy, a circuit which includes said electrically controlled pump driving means, said solenoid means and said switches, said switches being actuated by said cams at predetermined intervals and for predetermined periods to energize said pumping means and to operate said valve means for supplying lubricant to the measuring valves, an electrically energized warning signal, a circuit to connect said signal with said source of electrical energy, a normally closed and a normally open switch in said circuit, a pressure responsive device connected to a lubricant conduit leading from the pump to said measuring valves and operable in response to a predetermined pressure to open said normally closed switch, and means rendered effective by said duration cam to close said normally open switch during the period of operation of the pump for energizing the signal should the pump fail to develop a pressure at least equal to said predetermined pressure.

9. In a lubrication system which includes a series of measuring valves each adapted to deliver lubricant in response to pressure applied to the valve, conduit means connecting said valves in sequence, a supply of lubricant, a pump operable to feed lubricant under pressure from said supply to said valves, control valve means governing the application of pressure from the pump to the measuring valves, timing mechanism to control operation of said pump and control valve means, a plurality of switches operated by said timing mechanism to cause said pump and said control valve means to be actuated at predetermined intervals and for predetermined periods for supplying lubricant to the measuring valves, an electrically controlled warning signal, a circuit to control energization of said signal, one of said switches operated by said timing mechanism being rendered effective thereby to connect said signal circuit to said source of current at a predetermined interval after operation of the pump is commenced, and a pressure responsive switch to open said circuit in response to a predetermined increase in pressure in the system.

65. REUBEN WEDEBERG.
